US00D962939S

(12) **United States Design Patent** (10) **Patent No.:** **US D962,939 S**
(45) **Date of Patent:** **** Sep. 6, 2022**

(54) **COMPUTING DEVICE**

(71) Applicant: **Microsoft Corporation**, Redmond, WA (US)

(72) Inventors: **Timothy G. Escolin**, Seattle, WA (US); **Young Soo Kim**, Bellevue, WA (US); **Scott Schenone**, Seattle, WA (US); **Panos Costa Panay**, Redmond, WA (US); **Ralf Groene**, Kirkland, WA (US); **Byungkwan Min**, Kirkland, WA (US)

(73) Assignee: **Microsoft Corporation**, Redmond, WA (US)

(**) Term: **15 Years**

(21) Appl. No.: **29/707,916**

(22) Filed: **Oct. 1, 2019**

(51) LOC (13) Cl. **14-02**

(52) U.S. Cl.

USPC **D14/345**

(58) **Field of Classification Search**

CLAIM

The ornamental design for a computing device, as shown and described.

DESCRIPTION

FIG. 1 is a perspective view of a computing device showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depicting the remainder of the computing device in FIGS. 1-7 show features that form no part of the claimed design.

1 Claim, 5 Drawing Sheets
